UNITED STATES PATENT OFFICE.

MARY J. KOVACS, OF ST. CLAIRSVILLE, OHIO.

AUTOMATIC GATE FOR RAILWAYS.

Application filed May 11, 1927. Serial No. 190,463.

This invention relates to automatic gates for grade crossings, and has for its object to provide an apparatus of this character in which the guard, or closure elements are actuated by means of electro-magnets acting through a novel lever mechanism.

A further object is to provide means for closing the entrance gates in advance of the exit elements.

The device also comprises a novel form of contact switch, and strike bars adapted to operate same.

These and other objects and advantages are fully described in the following specification and claims and are illustrated in the accompanying drawings, in which:

Fig. 1 shows a front elevation of the gate with the closure elements in their lowered positions.

Fig. 2 shows a plan view of a grade crossing with the gates in position on both sides of the tracks.

Fig. 3 shows a wiring diagram for the installation as shown above, the arrangement being for a double track railroad.

Fig. 4 shows the location of the contact switches with respect to the rails on a single track road.

Fig. 5 shows an enlarged front view of the operating elements within a casing which rests upon a concrete pedestal.

Fig. 6 shows a plan view in section on the line 6—6 of Figure 5.

Fig. 7 shows the lower portion of a locomotive fender, or cow catcher, with a strike bar mounted thereon.

Fig. 8 shows a rear car platform with a strike bar of somewhat longer dimensions mounted thereon.

Fig. 9 shows an enlarged fragmentary view of a railroad track with top view of a contact switch mounted thereon, but insulated therefrom. A portion of the cover guard is cut away to disclose the contact plate.

Fig. 10 shows a front elevation of the switch as illustrated in Figure 9.

Before giving a detailed description of the device, I wish to emphasize certain features of particular importance in relation thereto.

First: The gates are automatically operated by means of heavy solenoid magnets as seen at 15 in Figure 5. Their motion being retarded by compression cylinders as that seen at 16 in the same figure.

Second: The gate element on the ingoing side as seen at 17 in Figure 1, is designed to close in advance of the outgoing gate element as seen at 18. The reason for this, is that while it is desirable to stop vehicles approaching the track as promptly as possible, it is also important that any similar vehicle which might be on the track at the moment of the gate closing, would by reason of the retarded action of the outgoing gate have ample time to pass out from the guarded area.

Third: The contact switch as seen at 19 in Figure 3 which is operated to close the gates on the approach of a train, is thrown by contact with a strike bar as seen at 20 in Figure 7 on the front part of the engine, but the contact switch 21 in Figure 3 which acts to re-open the gates, is actuated by contact with a strike bar 24 as seen in Figure 8, this being attached to the rear platform of the last car of a train. It will be seen that this arrangement provides for the closing of the gates well in advance of the arrival of the train at the crossing, but only opens them again after the last car has passed to a point of safety.

Fourth: In an installation at a crossing having double tracks, it is obvious, that should a train approach from the right and another train approach from the left a few moments later, the gates would be closed by the first train and would be opened again as soon as it had passed the crossing, unless means were provided to keep them closed until the second train had passed. Otherwise they would be opened as soon as the first train had passed, but at a time when the second train was close to the crossing. This would, of course, produce disaster, as vehicles would at once start to cross the tracks.

This difficulty is solved in the device here shown by the provision of the magnetic switches as seen in Figure 3 at 22 and 23. It will be seen that as both of these switches supply current to the magnet 15 and its companion magnet 24, these magnets will remain energized until both switches have been opened. That is, the first train will close the gates, and on passing will open the release switch for its own track, but the switch for the opposite track, being still closed, will keep the magnets 15 and 24 energized and the gates closed until opened by the passing of the second train.

These features will be more fully understood on reading the following specific details.

The apparatus comprises gate elements as seen at 17 and 18 in Figure 1, and at 25 and 26 in Figure 2, the elements being pivotally mounted within casings as that seen at 27 in Figure 5. Still referring to Figure 5, gears 28 and 29 are secured to the base ends of the gate elements. These gears mesh with toothed segments 30 and 31, which are integral with the levers 32 and 33 which are pivotally supported at 34 and 35 and are slotted as seen at 36. The segment 30 is toothed along its upper arc as seen at 37, but blank below that point. It will thus be seen that when actuated, it closes the gate at once and then moves freely to its upper position. The segment 31, however, is toothed on its lower arc as seen at 38 and when moved, does not engage the gate gear until the center of its movement is reached. The right hand elements are counterweighted as seen at 39 and the left elements as shown at 40, the left counterweight being directly on the gate element as there are no gear teeth in mesh to hold the gate in its upper position, as is the case on the right hand side.

Both levers are moved by the stud 43 which is on the bar 44. This bar being secured to the plunger of the operating magnet 15 at the bottom and to the connecting rod of the compression cylinder 16 at the top. It is guided by the lug 45. The compression cylinder has a vent as seen at 46 and a piston 47.

The right approach switch 22 is thrown by the opposed magnets 48 and 49 and the left approach switch 23, by the magnets 50 and 51.

The casing 27 is supported by a base 52, preferably of concrete, or the like.

Lower guard rails 52 and 53 seen in Figure 1, are attached to the gate elements.

Referring now to Figure 7, the advance strike bar 20 has a foot 56 and is pivotally secured to its upper element. It is held in its central position by the springs 57 and 58. The bar is supported by a socket plate 59 from which it may be removed by sliding upward. The said plate is secured to the lower rail if the engine fender 60.

The release strike bar is shown in Figure 8 at 24 and is provided with a foot piece 61 similar to that of the bar 20. It is pivotally mounted on a supporting member 62 which is secured to the car platform 42 by a socket member 63 in the same manner as that first described. It is held in centralized tension by the fork members 64 and 65 and the springs thereto attached.

Referring to Figures 9 and 10 of the drawings, the contact switch 21 is secured to the rail 66 and insulated therefrom as shown at 67. A vertical member 68 has secured there-

to the contact plate 69 which is insulated at its base end as shown at 70. The vertical member 68 passes beyond and covers the free end of the said contact plate. A protective guard 71 which is preferably of wood, covers the contact elements at the top. It will be seen that a strike bar approaching the end of the switch nearest to the track will engage the contact plate and close the electric circuit at that point, while a similar bar approaching the opposite end of the said switch will strike the back of the vertical member 68 and be shunted to one side where it will pass without affecting the said circuit.

In the wiring diagram in Figure 3, the right hand rails are seen at 82 and 83 and the left hand rails at 84 and 85. The source of current supply is indicated at 86. An approaching train closes the contact switch 19 and energizes the magnet 49 which closes the switch 22 and energizes the operating magnets 15 and 24 which are wired in multiple. When the rear strike bar engages the contact switch 21, the magnet 48 is energized and opens the switch 22 which releases the operating magnets 15 and 24 and opens the gates.

The magnets 50 and 51, with the switch 23 are also operated in the manner above described by a train approaching from the left and contacting with the switches 86 and 87.

Referring to the diagram in Figure 4, it will be seen that an advance strike bar as 56 contacts with the switch 19 to close the circuit, but on reaching the switch 87 would strike the guard member and be deflected on the inner side leaving the switch open, while the rear strike bar 61 would similarly close the switch 21, but pass freely on the inner side of the switch 86.

Bell, or lamp signals may be operated in conjunction with the gate operation, if desired.

While I have shown the preferred embodiment of my invention, I do not wish to be held rigidly to the exact details of form and construction as illustrated, but claim the right to such minor modifications as may come within the scope of the appended claims.

Having thus described my invention, what I claim as new and desire to secure by Letters Patent, is as follows:

1. In a device of the class described, the combination, with pivotally mounted gate elements, of gears secured to the said gate elements, coaxial with the pivot points, a means for normally holding the gates in raised position, levers pivotally mounted intermediate of their ends, segments formed on one of the ends of the levers, certain of these segments being provided with teeth along their upper arc portions, meshing with certain of the said gears for lowering the

gates connected with the gears immediately upon motion of the levers, and the other segments being provided with teeth along their lower arc portions, meshable with the other gears after a certain amount of free motion for lowering the gates connected with these gears a short time after initial motion of the levers, and a means connected with the free ends of the said levers for moving the levers in unison.

2. In a device of the class described, the combination, with pivotally mounted gate elements, of gears secured to the said gate elements, coaxial with the pivot points, a means for normally holding the gate in raised position, levers pivotally mounted intermediate of their ends, segments formed on one of the ends of the levers, certain of

these segments being provided with teeth along their upper arc portions, meshing with certain of the said gears for lowering the gates connected with these gears immediately upon motion of the levers, and the other segments being provided with teeth along their lower arc portions, meshable with the other gears after a certain amount of free motion for lowering the gates connected with these gears a short time after initial motion of the levers, the free ends of the levers being slotted, a stud engaged in these slots, a bar connected to the said stud, and a means for moving the said bar.

In testimony whereof I have affixed my signature.

MARY J. KOVACS.
